[57] CLAIM

The ornamental design for a valve body, as shown and described.

DESCRIPTION

FIG. 1 is a top, front, and right side perspective of a valve body showing our new design;

FIG. 2 is a top, rear, and left side perspective view body showing our new design;

FIG. 3 is a planar right side view thereof with actuators shown in dashed lines assembled to the body;

FIG. 4 is a planar left view thereof, with actuators shown in dashed lines assembled to the body;

FIG. 5 is a front elevation view thereof, the rear elevation view being a mirror image;

FIG. 6 is a top plan view thereof; and,

FIG. 7 is a bottom plan view thereof.

The broken line showing is for illustrative purposes only and forms no part of the claimed design.

FIG. 1

FIG. 2

FIG. 5

FIG. 6

FIG. 7
